UNITED STATES PATENT OFFICE.

CORNELIS VERWER, OF KROMMENIE, NETHERLANDS.

ACETYLENE-GAS GENERATOR.

SPECIFICATION forming part of Letters Patent No. 655,287, dated August 7, 1900.

Application filed July 7, 1899. Serial No. 723,075. (No model.)

To all whom it may concern:

Be it known that I, CORNELIS VERWER, manufacturer, a subject of the Queen of the Netherlands, residing at Noorderkerkbuurt 63, 5 Krommenie, Provinz Nord-Holland, in the Kingdom of the Netherlands, have invented certain new and useful Improvements in Acetylene-Lamps, of which the following is a specification, reference being had to the 10 accompanying drawings, in which—

Figure 1 is a vertical cross-sectional view of the lamp. Fig. 2 is a section on the line $x-x$, Fig. 1.

My invention relates to improvements in 15 acetylene-lamps.

The water-receptacle and the gas-holder of the improved lamp are arranged near each other in the body of the lamp, and the diaphragm or partition-wall between them is 20 formed by a plate or sheet of india-rubber or other suitable material. From the water-receptacle the water passes in drops through a narrow tube into the carbide-receptacle. This carbide-receptacle is made in cartridge form 25 and consists of a closed sheet-metal cylinder of white iron, with a central open tube. Around this tube is the space in the cartridge which is filled with carbide. The central tube is not water-tight, but is made in such a manner 30 that the water can penetrate on all sides and can come into contact with the carbide. This object can be attained in various ways.

A simple solution which I have adopted in my improved acetylene-lamp consists in forming 35 the tube of a spirally-coiled strip of sheet metal wound so as to leave sufficient space between the edges of the several convolutions to permit the passage of water between them. The gas formed enters the gas-holder through 40 a connecting tube or passage of small bore and from thence passes through the burner to the flame. If the supply of gas is too great—that is to say, if more gas is generated than is required for feeding the flame—the 45 pressure will rise in the gas-holder. This increased pressure will cause the india-rubber diaphragm to be bulged out or distended, and this distention will cause the supply of water to be arrested. For this purpose a thin 50 sheet-metal plate is arranged to rest against the india-rubber diaphragm, which plate follows the motion of the said diaphragm and is

situated at the end of the long arm of a bell-crank lever. The short arm of this lever bears at its end an india-rubber block or 55 plate arranged directly above the opening or mouth of the water-tube. If the pressure rises in the gas-holder, the said india-rubber block or plate will be pressed onto the mouth of the water-tube by reason of the motion of the 60 above-mentioned metal plate, due to such increase of pressure, and thus the supply of water will be arrested until the pressure has been reduced to such an extent that the india-rubber diaphragm, and consequently also 65 the metal plate resting against it, have again taken up their normal position.

Referring to the drawings, a is the water-chamber, and b the gas-chamber, which are made of hemispherical form and are separated 70 by an india-rubber diaphragm c , the edge of which is secured between the flanged edges g and d of the two hemispheres. In this manner a hermetically-tight partition is obtained between the water and gas chambers. The 75 rear hemisphere a is provided with an eye h for suspending or securing the lamp and is made with a tubular extension z at the bottom, so as to form a joint-piece, which is provided with an internal screw-thread and a 80 flange i . The tube or shell j for receiving the carbide-cartridge l is screwed into this joint-piece z and a hermetically-tight joint made with the flange i thereon by means of an india-rubber ring k . In the front hemisphere 85 b is mounted the reflector e , and into this opens the burner f . A part of the said reflector forms the front wall of the gas-chamber b . In the middle of the cartridge is arranged a tube m , coiled up from a strip 90 of sheet metal. In this tube is placed a fine water-tube n , secured to the water-receptacle a , which tube n extends into the cartridge l nearly to the bottom thereof. Above the mouth of the said water-tube n lies the india-rubber valve o , by means of which the mouth 95 of the said water-tube n can be closed. The motion of this valve is effected by means of a wire q , bent in the form of a bell-crank lever and journaled at r in a bracket s at 100 the bottom of the water-chamber, close to the partition-wall. On the horizontal short arm of this lever is secured the india-rubber valve o . The vertical long arm has soldered

thereto a metal plate *p*, which is continually pressed by a feeble spring *s* against the india-rubber diaphragm *c*. One end of the spring *s* is secured to the valve *o*, and the 5 other end bears against the wall of the water-receptacle, the intermediate portion forming a coil. The springs tend to hold the valve raised and through the bell-crank the plate *p* against the diaphragm *c*. As the top of 10 the cartridge is closed around the tube *m* by a plate *l'*, the gas as generated passes through the said tube *m* and into a space between said plate *l'* and a plate *l²* in the tubular extension 2. This space communicates with 15 the gas-chamber *b* through a tube *t*, which passes through the plate *l²* and the shell of the chambers *a* and *b*.

A screw-threaded stem *v* extends from the plate *p* back through the wall of the receptacle *a*, on which a sleeve *w* is threaded. The sleeve is journaled in the wall of the receptacle *a* and carries at its outer end a nut *w'*, which normally bears on the exterior of said receptacle, so that by turning the same the 20 sleeve will turn and draw the plate *p* over to close the valve *o*. A stop-flange *x* is fixed to the sleeve, which limits the movement of the plate *p* when acting under the influence of the diaphragm *c*. The water-receptacle is 25 provided with an aperture closed by a screw-plug *u*, which can be removed to permit filling of the said receptacle.

The method of operation of the lamp is as follows: The water from the water-receptacle 30 *a* drops through the very fine water-tube *n* into the central coil-tube *m* of the cartridge and there comes into contact with the carbid. The acetylene gas generated rises between the two tubes *n* and *m* and passes through 35 the tube *t* into the gas-holder *b*. If more gas is generated than is necessary for feeding the flame, the pressure rises in the gas-chamber and the india-rubber diaphragm *c* bulges outward toward the water-chamber *a*. The plate 40 *p* follows this motion and transmits it by means of the lever-arm *q* to the valve *o*, which is thus pressed into the mouth of the water-tube *n* and the water-supply arrested. Further generation of gas cannot then take place. 45 The pressure in the gas-holder then falls, since the gas is gradually consumed by the flame. Thus the diaphragm *c* resumes its normal shape, (shown in Fig. 1,) the valve *o* opens under the action of the spring *s*, and water 50 again flows into the cartridge, so that generation of gas begins afresh. When it is desired to extinguish the light, the valve *o* is closed by simply screwing up the nut *w*. The arrangement is thus extremely simple, the 55 action perfectly certain and free from danger, and the manipulation easy.

The carbid-cartridges, which are delivered closed, can be conveniently carried and can be thrown away as soon as they are exhausted, 60 so that one has nothing to do with the unpleasantly-smelling residue.

When it is desired to insert a fresh car-

tridge, the valve *o* is closed, the outer tube *j* unscrewed, the old cartridge replaced by a fresh one, the said tube screwed in again, and 70 finally the valve *o* opened.

The several parts are so arranged that they can be easily taken apart for carefully cleaning the lamp.

The form and ornamentation of the lamp 75 can be varied as desired. My improvements are more particularly suitable for velocipede-lamps, but can also be applied to carriage-lamps or chamber-lamps. Danger of explosion is precluded, and the action is quite automatic.

If it be desired to employ a glass in front of the reflector, the burner should be placed upright and the reflector provided with air-holes.

Since the regulation and extinguishing of the flame are effected by simply turning the screw-nut *w*, the manipulation is very simple and can take place from the saddle.

What I claim is—

1. In an acetylene-lamp, the combination, with a gas-chamber, of a water-chamber adjacent thereto, a vertical elastic partition wall or diaphragm between said gas-chamber and said water-chamber, a carbid-receptacle, a passage connecting said water-chamber and said carbid-receptacle, a bell-crank lever in said water-chamber, a plate mounted on one arm of said lever and pressed by spring-pressure against said diaphragm and a valve 100 mounted on the other arm of said lever, and controlling said passage, substantially as, and for the purposes, hereinbefore described.

2. In an acetylene-lamp, the combination with a gas-chamber, of a water-chamber adjacent thereto, an elastic diaphragm separating said gas and water chambers, a carbid-receptacle, a passage connecting said water-chamber with said carbid-receptacle, a valve controlling said passage, and a pivoted lever 105 engaging said diaphragm and said valve, substantially as, and for the purposes, hereinbefore described.

3. In an acetylene-lamp, the combination with a gas-chamber, of a water-chamber adjacent thereto, an elastic diaphragm separating said gas and water chambers, a carbid-receptacle, a passage connecting said water-chamber with said carbid-receptacle, a valve controlling said passage, a pivoted lever for 110 transmitting the motion of said diaphragm to said valve, and means to actuate said lever by hand, substantially as, and for the purposes, hereinbefore described.

4. In an acetylene-lamp, the combination, 115 with a gas-chamber, of a water-chamber adjacent thereto, an elastic diaphragm separating said gas and water chambers, a carbid-receptacle, a passage connecting said water-chamber with said carbid-receptacle, a valve 120 controlling said passage, a spring-pressed bell-crank lever engaging said diaphragm and said valve, a screw-threaded rod pivotally connected to said lever, a stop on said

rod adapted to engage the frame of the lamp, and a screw-nut on said rod, substantially as, and for the purposes, hereinbefore described.

5. In combination in an acetylene - gas lamp, a body portion comprising a gas-chamber and a water-chamber, and a depending tubular portion, a carbid-holder held therein, a chamber in said tubular portion above the carbid-holder, a passage between the 10 same and the gas-chamber, a tube extending through the carbid-chamber open at its upper end, a tube depending from the water-chamber in the body portion through said open tube, and means for controlling the 15 mouth of the depending tube, substantially as described.

6. In combination in an acetylene - gas lamp, a body portion comprising a gas-chamber and a water-chamber, and a depending

tubular portion, a carbid-holder held therein, a chamber in said tubular portion above the carbid-holder, a passage between the same and the gas-chamber, a tube extending through the carbid-chamber open at its upper end, a tube depending from the water-chamber in the body portion through said open tube, a flexible diaphragm dividing the water from the gas chamber, and a tilting valve controlled by said diaphragm adapted to close the end of the depending tube, substantially as described. 20 25 30

In witness whereof I have hereunto set my hand in presence of two witnesses.

CORNELIS VERWER.
